UNITED STATES PATENT OFFICE.

H. C. SMITH, OF CLEVELAND, OHIO.

IMPROVEMENT IN HARVESTERS.

Specification forming part of Letters Patent No. 19,590, dated March 9, 1858.

To all whom it may concern:

Be it known that I, HENRY C. SMITH, of Cleveland, in the county of Cuyahoga and State of Ohio, have invented new and useful Improvements in Harvesters; and I do hereby declare that the following is a full and complete description of the construction and operation of the same, reference being had to the accompanying drawings, and to the letters of reference marked thereon, making part of this specification, in which—

Figure 1 is a perspective view. Fig. 2 is a plan view. Fig. 3 is an end elevation. Fig. 4 is a rear view, and Fig. 5 sectional parts.

The driving-wheel A is constructed in the usual form, one only being used. A cog bevel-gear, B, is attached to the arms of the wheel A, just inside of the tread. A shaft, C, passes through the center of the hub, and upon this the wheel revolves. The shaft or axle C extends upon either side of the hub a sufficient distance to receive the frame D and drag-bar E, both of which articulate upon the shaft or axle C. The arm D' is a continuation of the frame D, and turns at right angles at D'', and terminating upon a line with the middle of the wheel A.

Between the frame D and the wheel A, upon the inside and attached to the hub of the wheel, is a pulley, F, which serves to drive the reel. The cutter-bar G is rigidly attached to the drag-bars E E, and is constructed in the usual form, and is furnished with the usual appendages of fingers, knives, &c.

For the purpose of raising and lowering the cutter-bar at pleasure, I introduce a system of levers, H I J. The lever H is placed upon the right hand and a little in front of the driver's seat K, so that he can take hold of it with his right hand. The fulcrum of the lever H is upon the forward end of the frame D at H'. The short arm of the lever H'' takes hold by a pin-joint of the connecting-rod L. This connecting-rod L is in like manner attached at its upper end to the lever I, whose fulcrum is upon the axle C. The arm I forms a slight angle with the drag-bar E, to which it is rigidly attached at the points where the axle C passes through both, as seen at I', Figs. 2 and 3. Consequently when the lever H is drawn back toward the seat the forward end of the lever I is depressed and the tail end of the drag-bar E and cutter-bar G raised from the ground to an

extent corresponding to the distance the lever H is drawn back. The lever I can be supported at any point by a pin introduced into any of the holes in the support M.

For the purpose of raising the outer end of the cutter-bar the same distance and simultaneously with the right-hand end, I introduce the curved lever J, which has its fulcrum at N just above the back right-hand corner of the drag-bar E. The long arm of this lever J has a slot at the end, as seen at O, Fig. 4, which plays upon a pin or wrist, O', upon the end of the arm D''. To the short arm of this lever J is attached a rod or cord, as seen at P, Fig. 4. This rod or cord extends along the back edge of the cutter-bar G between two protecting plates, as seen at P P' in Figs. 2 and 4. The rod or cord P P', or equivalent, should be formed of short links, or of some flexible material at the P' end, so as to enable it to pass upward from beneath the roller Q, from whence it passes to and takes hold of the cross-bar R, that connects the bent levers R' R' about one-third of the distance from the fulcrum end of these levers. The roller Q is secured to a plate, T, (seen in Fig. 5,) which rests upon and is secured to the outer end of the cutter-bar. The fulcrum of the levers R' R' is in the plate T and on a line with its upper surface. The outer end of the levers R' R' support the wheel S, which rests upon the ground and carries the weight of the outer end of the cutter-bar and its appendages. The position of the wheel S and the levers R' R' when the cutter-bar is working close to the ground is seen in Fig. 3, the lever H being in the position shown in Fig. 3—that is, the lever is not drawn back toward the seat K.

Whenever it is desired to raise the cutter-bar to pass over obstructions or to cut higher from the ground, the lever H is drawn back toward the seat K. This movement depresses the lever I and raises the drag-bar E. This moves the lever J on the pin O' in the direction of the arrow 1, ($\leftarrow 1$), the short arm of the lever J moves in the opposite direction and draws the rod P P' in the direction indicated by the arrow 2, ($\rightarrow 2$), and this movement acting upon the levers R' R', the outer ends of which are supported by the wheel S, the fulcrum end is necessarily elevated, and with it the cutter-bar. This brings the wheel S and the levers R' R' into the position seen in Fig. 5, when the lever H is drawn entirely back.

The elevation, therefore, of the cutter-bar will depend upon the position of the lever H, and by introducing a pin at M it can be kept stationary at any desired point between the two positions shown in Figs. 3 and 6.

For the purpose of keeping the cutter-bar as nearly horizontal as possible—in other words, to adapt the harvester to teams of different heights—I introduce a neap, U, Fig. 6, having a joint, U', with a gage, V, secured by a pin, V'. This enables the operator to give to the fingers of the cutter-bar any desired pitch or inclination upward or downward, even without reference to the height of the team, or to keep them in a horizontal position, as above described, if desired.

I do not claim any of the devices herein named and described as new in themselves considered or detached from each other; but what distinguishes my improvement from all others relates to the manner of elevating and depressing the cutter-bar by means before set forth, and also in giving any desired pitch to

the fingers, or keeping them in a horizontal position by means of changing the relative position of the neap in reference to the frame D and drag-bars E E, and at the same time changing the point of draft as the nature of the case may require.

What I claim as my improvement, and desire to secure by Letters Patent, is—

The manner herein described of raising and lowering the cutter-bar by the combined action of the levers H I J, the flexible rod or cord P P', levers R R', and wheel S. This I claim when constructed and relatively arranged and operating as described, and also when used in connection with the drag-bars E E articulating upon the axle C, as set forth, for the purpose specified.

H. C. SMITH.
